UNITED STATES PATENT OFFICE.

JACQUES LOUIS KESSLER, OF CLERMONT-FERRAND, FRANCE.

APPARATUS FOR CONCENTRATING SULFURIC ACID.

SPECIFICATION forming part of Letters Patent No. 651,717, dated June 12, 1900.

Application filed January 4, 1899. Serial No. 701,133. (No model.)

To all whom it may concern:

Be it known that I, JACQUES LOUIS KESSLER, a citizen of the Republic of France, residing in Clermont-Ferrand, Puy-de-Dôme, France, have invented an Improved Apparatus for Concentrating Sulfuric Acid, of which the following is a specification.

This invention relates to an improved apparatus for concentrating sulfuric acid by contact with heated gases.

The invention is more especially an improvement upon the apparatus for which I obtained Letters Patent No. 520,994, dated June 5, 1894.

15 The construction of this improved apparatus is such that the cleaning of the saturating-chamber and of the plates of the recovery-column is facilitated, that the said plates are of a simpler construction and insure a more 20 convenient maintenance, and that consequently it is possible to treat in the said apparatus sulfuric acid containing impurities, such as the acid obtained from Glover's apparatus and that obtained by reusing the residues from the acids of nitration of organic 25 acids.

In the accompanying drawings, Figure 1 is a vertical section through the concentrating apparatus constructed in conformity with my 30 invention, taken on the line 1 1 of Fig. 2. Fig. 2 is a horizontal section through the said apparatus on the line 2 2 of Fig. 1. Fig. 3 is a cross-section on the line 3 3 of Fig. 2. Fig. 4 is a plan of one of the plates of this apparatus. Figs. 5 and 6 are sections taken, respectively, on the lines 5 5 and 6 6 of Fig. 4. Fig. 7 is a plan of another form of plate device capable of being employed in the apparatus. Figs. 8, 9, and 10 are sections taken, respectively, on the lines 8 8, 9 9, and 10 10 of Fig. 7.

The concentrating apparatus represented in Figs. 1, 2, and 3 comprises, like my previous apparatus, a saturating-chamber A, receiving the acid to be concentrated and being 45 subdivided in a number of channels *a*, through which the hot gases serving to produce the concentration circulate. These gases enter by way of the flue B and the conduits *b*, pass through the said channels *a*, act upon the 50 face of the acid, escape below the partitions C through the conduits *a'* into the chamber D, and escape from the apparatus by way of the

chimney E after having traversed a range of superposed perforated plates F. These plates receive the sulfuric acid prior to its introduction into the saturating-chamber A and deprive the gases of the greater part of their heat before they leave the apparatus through the chimney E. The chamber A and the column of plates are inclosed in a leaden jacket, 55 and the whole rests upon a metallic bed supported by columns P. Each plate F is, moreover, furnished with a hooked mounting to facilitate its removal when necessary. The leaden flanges of each plate are soldered together in such a manner as to form a continuous lead jacket.

The partitions C of the chamber A are formed according to the present invention by molding compressed materials of pumice 70 moistened with a solution of an alkaline silicate of 20° or 30° Baumé, then dried and even more or less calcined, whereas up to the present time they were formed of cut or chiseled stone. Silicious sand or pulverized glass 75 or crystal or a mixture of these different materials may be used in place of pumice. The longitudinal channels formed by these partitions C—that is to say, the channels *a*, through which the gases pass, as well as the conduits 80 *a'*, leading to the chamber D—have their ends provided with openings, which are respectively closed by stoppers or plugs *b*, of refractory stone. These plugs when put in place are cemented with clay. When they are 85 removed, it is possible to introduce into the channels *a* *a'* suitable tools to detach deposits of any nature that may have formed and that will obstruct said channels. At one of the ends of the chamber A a transverse 90 gutter *d* is arranged, terminating in lateral openings *d'*, each leading into a leaden conduit *e*, closed by a leaden plate *e'*, secured, by means of iron caps, to the flange of the said conduit. These lateral openings may be 95 simply closed with plugs of stone, which resist the action of acid; but in this case it is preferable that the said plugs be externally covered with a leaden plate soldered onto the leaden jacket of the chamber in order to 100 avoid any chance of escape.

The detached deposits above referred to are collected in the gutter *d* in order to be removed, by means of a scraper or rake, through

the suitable uncovered openings *d*. After the cleaning has been effected—that is to say, after the chamber has been freed from its deposits—the openings are reclosed, as above 5 explained, and a physical washing operation is employed by means of water or a weak acid, with which the chamber A is filled up to its overflow-level.

It should be understood that the openings in 10 question may be provided upon one side only or may be alternating from one side to another instead of being formed upon opposite faces, as represented.

When cleaned, the apparatus is recharged 15 and again started. It is preferable that during the operation an acid layer of about ten to fifteen centimeters in height be maintained instead of a layer of only from five to eight centimeters, as has heretofore been the case.

20 Under these conditions the salines of sulfate of iron and of sulfate of alumina, which constitute the greater part of the deposits which are formed in this layer, have time to become granular and to swell. They are then carried 25 away to a lesser degree, and owing to their immediate precipitation they leave an acid clear and non-turbid.

The plates F of the apparatus are formed, as represented on Figs. 1, 3, 4, 5, and 6, of 30 slabs with annular flanges, in which lateral openings are provided, closed by the aid of plugs *g*, of inattackable stone, which may be covered by small plates of lead soldered to the leaden outer jacket of the plates. The 35 openings in question serve to facilitate the cleaning of the plates and the replacing of their inner pieces. The plates each comprise for the discharge of the acids a siphonal piece of porcelain *h*, forming at once an overflow 40 and a hydraulic seal.

In the device represented in Figs. 7 to 10 the porcelain pieces *i* of the device represented in Figs. 4 to 6 are completely omitted. These pieces *i* are replaced in this case by a 45 particular shape imparted to the plates F. These plates are here so cut at their upper parts as to present an annular flange *j* and for each of the holes for the passage of the gases a sloping flange *k*. At their lower part cavities *l* are provided, which lie exactly above 50 the passage-holes of the lower plate and are formed not unlike caps or pans, serving to cause the gases to impinge against the surface of the liquid. It is evident that the

flanged passage-holes may be combined with 55 turned-back porcelain caps or pans and that in this case the cavities provided higher up would be omitted. In like manner the holes with flanges may be furnished with porcelain for the purpose of guarding against rupture 60 of the cut flanges. The plates in the device are likewise provided with cleaning-openings, closed by plugs *g*, and a sight-hole *h*, likewise closed by a stone plug. The apparatus improved in all its parts in the manner stated 65 is then more suitable for concentrating sulfuric acids containing impurities of a nature such as to cause deposits during the operation, more especially of acids obtained from Glover's apparatus and of those produced by the reemployment of residues resulting from acids of nitration or organic substances.

I claim as my invention—

1. An improved apparatus for concentrating 75 sulfuric acid and comprising inlet-conduits for the gas, a chamber A having dividing-partitions C forming longitudinal channels communicating with each other under the dividing-partitions, and provided with 80 outlets for the gas and removable plugs at the ends of each of the aforesaid channels, as and for the purpose described.

2. An improved apparatus for concentrating 85 sulfuric acid and comprising inlet-conduits for the gas, a chamber A having dividing-partitions C forming longitudinal channels communicating with each other under the dividing-partitions, and provided with outlets for the gas, removable plugs at the 90 ends of each of the aforesaid channels, a transverse gutter in the bottom of the chamber and a discharge-opening from the gutter, substantially as described.

3. An improved apparatus for concentrating 95 sulfuric acid, and comprising a saturating-chamber with superposed recovery-column consisting of a series of perforated plates, having flanges with openings closed by removable plugs, as and for the purpose described. 100

In testimony whereof I have signed my name to this specification in the presence of two subscribing witnesses.
